UNITED STATES PATENT OFFICE.

WILLIAM A. PRENTISS, OF HOLYOKE, MASSACHUSETTS.

COLLAPSIBLE SPOOL.

Application filed December 4, 1922. Serial No. 604,871.

To all whom it may concern:

Be it known that I, WILLIAM A. PRENTISS, a citizen of the United States of America, residing at Holyoke, county of Hampden, 5 State of Massachusetts, have invented certain new and useful Improvements in Collapsible Spools, of which the following is a specification.

This invention relates to improvements 10 in collapsible spools particularly for use in winding wire or other material thereon so that when the coil of wire is completed it may be readily removed from the barrel or hub part of the spool.

15 Broadly considered it comprises a spool having the usual head or end members and a plurality of movable arc-shaped sections which compose the barrel or hub part of the spool on which the wire is wound, said 20 sections being so constructed and arranged with relation to the head members that when one of the head members of the spool is removed the barrel sections will automatically collapse or assume a position the 25 diameter of which is less than when the coil of wire is being wound, one of the head members serving to automatically move the arc-shaped sections composing the barrel outwardly when the two members are connected or clamped rigidly together for winding the wire.

30

It is a well known fact that unless some means is provided for causing the sections of the barrel or hub part to collapse after the coil is wound it cannot be readily removed.

As a modification my improvement embodies a collapsible barrel or hub in which the sections thereof are composed of arc-shaped members with their opposite ends formed with inclined surfaces to engage inclined surfaces on the two head members, whereby when the head members are drawn toward each other and clamped, the barrel 45 elements are forced radially outwardly and will automatically collapse, or move radially inwardly toward the axis of the spool when the securing means is removed. In this class of invention it is very necessary that the entire length of the barrel or hub 50 elements will move inward and parallel to the axis in order that the wire which engages the sections of the barrel is properly released the entire length of the same so that the finished coil may be removed.

Referring to the drawings:

Fig. 1 is a sectional view on a plane represented by the line 1-1 of Fig. 2 showing the pivotal connection of one of the arc-shaped barrel sections which composes the 60 completed barrel or hub attached to one of the head members, also the removable head member which engages the barrel sections and the securing bolt.

Fig. 2 is a view looking from the right 65 of Fig. 1 with the removable head member withdrawn from the securing bolt.

Fig. 3 is a detail view of one of the barrel sections.

Fig. 4 is a view showing the inner surface 70 of the removable head member and illustrating the pin which engages a recess in one of the arc-shaped barrel sections.

Fig. 5 is a detail view looking towards the inside of one of the arc-shaped barrel 75 sections.

Fig. 6 is a sectional view on a plane indicated by the line 6-6 of Fig. 7 showing a modification of the arc-shaped barrel section and the two head members, and the 80 sections located on the fixed shaft or core of the spool.

Fig. 7 is a view showing the inner surface 85 of the removable head of Fig. 6 and illustrating the rectangular shaped shaft or core with the arc-shaped sections thereon and the circular opening through which the securing bolt passes.

Fig. 8 is a detail view of two of the arc-shaped sections located on the rectangular 90 shaped shaft.

Fig. 9 is a detail view of one of the intermediate arc-shaped barrel sections which are located on the rectangular shaped core.

Fig. 10 is a perspective view of one of 95 the sections shown in Fig. 9 and illustrating the rectangular shaped opening there-through which receives the shaft, and

Fig. 11 is an assembled view before the removable head piece is placed on the core. 100

Referring to the drawings in detail:

1 designates which may be termed the fixed head or member of the spool and 2 the removable head. The head 1 is formed with a depression or annular recessed portion 3 105 in the inner face thereof and a hub portion 4. Pivotally connected to the member 1 are four arc-shaped barrel sections indicated in Fig. 2 by the numerals 5, 6, 7 and 8 and in the detail view in Fig. 3. 110

It is to be understood that I do not limit myself to any particular number of these arc-shaped sections which go to make up the barrel part of the spool, as the number four shown is merely illustrative. Each of these sections is pivotally attached to the head 1 by means of the posts or studs 9 permitting them to swing about this pivotal connection as indicated by the dotted line 10 in Fig. 2 and engage the edge of the recess 3 of the head 1. It will be observed that these sections move parallel to the axis of the spool. The outer or right hand ends of each of the sections 5, 6, 7, and 8 are formed with an inclined surface 11 on the inner surfaces thereof and engaging each of these inclined surfaces is an inclined surface 12 on the integral flange 13 of the removable head member 2, whereby when the nut 21 on the bolt 14 is tightened the head member 2 is drawn toward the left from the dotted line position 2' to the full line. This will cause each of the arc-shaped sections 5, 6, 7, and 8 to turn on their pivots and be forced outwardly or radially from the axis and rigidly clamped in this position. The head member 2 is formed with a stud 15 which engages one of the recesses 16 in one of the arc-shaped barrel sections. This is for the purpose of causing the head 2 to revolve with the head 1 which is provided with a recess 17 to receive a pin on the driving element of the machine when the spool as a whole is rotated, to wind the wire indicated at 18 on the barrel section. It will be seen from Fig. 2 that when the arc-shaped barrel sections are in their normal or operative position, or in other words, when they are forced outward the wire indicated at 18 is therefore wound around the outer arc-shaped surface 20 of each of these sections and across the openings 19. When the removable head is withdrawn by removing the nut 21 the pressure of the inner turns of the wire coil on the arc-shaped barrel sections will automatically cause all of these sections to swing inward about their pivots toward the axis, thus forming in effect a collapsible barrel or hub, the outer arc-shaped surfaces 20 of which move inward parallel to the axis so that the coil of wire which has been wound on the surfaces 20 is free to be withdrawn from the barrel. This is an important feature as it automatically permits the barrel elements to release the coil of wire throughout its entire length or whole inner surface of the coil. The inclined surfaces 11 and 12 between these sections and the removable head 2 rigidly retains the arc-shaped sections in place while the wire is being wound. The inner surface end of the sections 5, 6, 7, and 8 is formed with a flange or rim 21 which engages the annular or recessed portion 3 of the hub 1. Therefore the opposite ends of the arc-shaped sections are firmly retained

in place; one by the head 2 and the other by the recess 3 and studs 9.

Referring to the modification shown in Figs. 6 to 11 inclusive, 22 and 23 designate the fixed and removable head members of the spool, the member 22 is provided with an integral shaft or hub 24. This hub as shown in Figs. 7 and 8 is rectangular and has a circular opening 24', to receive a clamping bolt. The vertical distance, indicated by the numeral 25 is more than the transverse distance indicated by the numeral 26. This is for the purpose of permitting the arc-shaped sections which compose the barrel to move radially inward toward the axis when the head member 23 is removed. Each one of these sections is formed with inclined end surfaces 27 and 28 which engage and contact with correspondingly shaped inclined surfaces 29 and 30 on the two head members 22 and 23 as shown. The effect of this construction is that when the head member 23 is tightened by the nut 21 the inclined surfaces will force the four arc-shaped sector sections 31, 32, 33, and 34 outward and at the same time always maintain a parallel position with the axis. The dotted line 35 indicates their position before being radially forced outward as shown in Fig. 6. The end sectors 31 and 33 are formed with inwardly extending integral portions 36 and 37 having rectangular shaped openings to receive the rectangular shaped shaft or hub 24, but the dimensions of the openings in these parts 36 and 37 is such that they may move radially of the axis. The spaces 38 and 39 permit this radial movement. The extent of radial movement is indicated in Fig. 7 at 38'. Located intermediate of these members 31 and 33 are the two arc-shaped sections 32 and 34, see Fig. 11.

It will be seen that the arc-shaped sections 31, 32, 33, and 34 may move radially of the axis when the head 23 is bolted or clamped and will automatically assume the dotted line position, indicated at 35, when the head 23 is removed. Fig. 10 is a detail view of one of the arc-shaped elements showing the rectangular shaped opening 40 which extends through the part 36, which engages the rectangular shaped shaft or hub 24 of the spool. The vertical distance 40' of this opening, is, as stated, greater than the vertical distance of the shaft 24 whereby the arc-shaped sector may move radially of the shaft.

It will be noticed that in both of the forms of the spool is involved the principle of movement of the arc-shaped barrel sections that is parallel to the axis of the spool when the removable head is tightened or loosened in order that the coil of wire may be readily removed from these sections. In the forms shown in Figs. 1 to 5 the sector or arc-shaped elements are pivotally con-

nected to the fixed head 1 and in the forms shown in Figs. 6 to 11 the arc-shaped sections are slideable radially of the shaft or hub of the fixed head 22 but move outwardly and inwardly when they are clamped or released. In Fig. 6 are shown stop pins 41' for retaining the arc-shaped members 31 to 34 in place on the hub.

It will be observed that the oppositely located sections 31 and 33 will move toward and away from each other, and the oppositely located sections 32 and 34 will also move toward and away from each other but at right angles to the other two sections. 15 31 and 33 may be termed the end sections and 32 and 34 the intermediate sections. The spaces 31' and 33' under the sections 31 and 33 permits the extensions 32' and 34' to move radially. The direction of 20 movement of the arc-shaped members 31, 32, 33, and 34 is indicated by the arrows 41, 42, 43 and 44.

The radially arranged slots 22' and 23' in the heads 22 and 23 are for inserting the 25 inner end of the coil of wire for retaining it in place while being wound and for banding the coil before removal.

When the arc-shaped sections 31, 32, 33, and 34 collapse or move towards the axis 30 the openings 45, 46, 47, and 48 will be more or less closed as shown by the dotted lines in Fig. 11. The full lines represent the open positions or winding positions.

What I claim is:

35 1. A spool for the purpose described, comprising a fixed and a removable head, the fixed head having a plurality of arc-shaped members movably engaging the same and movable relative thereto, one of 40 the ends of these members having inclined surfaces, the removable head having a cooperating inclined surface to force or move the arc-shaped members outward on the fixed head when the removable head is 45 clamped thereto.

2. In a spool, the combination, of a fixed and a removable head, the fixed head having a recess formed on its inner face, a plurality of arc-shaped barrel sections engaging the recess of the fixed head and movable relative thereto in the recess, the removable head having an inclined part engaging the arc-shaped barrel forming sections for moving the same radially outward 50 when the head is secured to the fixed head of the spool.

3. In a spool, the combination, of a fixed and a removable head, the fixed head having a hub, a bolt passing through the hub 55 for clamping the removable head in place, a plurality of barrel sections interposed between the two heads, one of the heads having an inclined surface cooperating with correspondingly shaped inclined surfaces on the barrel sections for moving these sections

radially outward and simultaneously maintaining the sections in parallel relation to the axis when the removable head is clamped in place or removed.

4. In a spool for the purpose described, 70 the combination, of a fixed and removable head, a plurality of movable sector elements interposed between the heads for receiving the wire which is wound on their outer surfaces, said elements being spaced from each other when clamped in position, means including inclined cooperating surfaces on one of the heads and the sector elements for permitting the elements to move inward and in parallel relation to the axis when the 75 clamping means is removed, whereby the coil of wire which has been wound on these elements may be readily removed from the collapsed sector elements.

5. In a spool, a fixed and a removable 85 head, the fixed head having a plurality of sectors engaging the same and movable relative to the head, the outer ends of the sectors having inclined surfaces, the removable head having a flange formed with an inclined surface for engaging the inclined surfaces of the sectors for moving them outward and on the fixed head, means for securing the heads together.

6. In a spool, the combination, of a fixed 90 head, a removable head, a plurality of arc-shaped sections interposed between the heads, wedging means on one of the heads for simultaneously moving all of the sections outward and in parallel relation to the axis, means for securing the sections in 95 this position.

7. In a spool, the combination, of a fixed 100 head, a removable head, a plurality of arc-shaped sections interposed between the heads, means for simultaneously moving all of the sections outward and in parallel relation to the axis, means for securing the sections in this position, said moving means including inclined or wedging surfaces between the removable head and said sections.

8. In a spool, the combination, of a fixed 105 and a removable head, a plurality of arc-shaped sections which compose the barrel part of the spool and in spaced or separated positions when the material is wound thereon, means on the removable head for forcing the sections into this position but permitting them to collapse or move towards the axis and in parallel relation thereto 115 when the removable head is withdrawn, and means for securing the parts in operative positions.

9. In a spool, the combination of a fixed 120 and a removable head, one head being formed with a groove having an inclined surface, the fixed head having a hub attached thereto, a plurality of barrel forming sections interposed between the heads and movable radially of the axis of the 125 130

4

spool, said sections having inclined surfaces for engaging the inclined surface of the groove in one of the heads, for the purpose of supporting the sections at one of their ends and for causing the sections to move outward when the removable head is moved towards the fixed head, and means in the hub for clamping or securing the two heads and said sections in place.

10. In a spool, the combination of a fixed and a removable head, each formed with a groove having an inclined surface, the fixed head having a shaft attached thereto, a plurality of barrel forming sections slidably mounted on the shaft for permitting move-

ments longitudinally and radially of the axis of the spool, said sections having inclined surfaces for engaging the inclined surfaces of the grooves in the heads, for the purpose of supporting the sections at their ends and for causing the sections to move outward when the removable head is moved towards the fixed head and means for clamping or securing the two heads and said sections in place, the construction and arrangement of the sections and shaft being such that some of the oppositely located sections will move simultaneously and transversely to the other sections.

20 25 WILLIAM A. PRENTISS.
